(57) **CLAIM**

The ornamental design for a decorative tire, as shown and described.

DESCRIPTION

FIG. 1 is a perspective view of a decorative tire of the present invention; the dotted lines demonstrate a wheel the tire is mounted on are for illustrative purposes, no claim is being made for the dotted lines that make up the wheel;

FIG. 2 is a perspective view of the decorative tire thereof;

FIG. 3 is a top plan view thereof;

FIG. 4 is a bottom plan view thereof;

FIG. 5 is a right side view thereof; and,

FIG. 6 is a left side view thereof.

The broken line showing of environment is for illustrative purposes only and forms no part of the claimed design.
